SANITARY NAPKIN

Elizabeth Dudley, Rose Valley Road, Wallingford, Pa.

Filed Jan. 8, 1960, Ser. No. 58,969

Term of patent 14 years

(Cl. D83—1)

I claim:

The ornamental design for a sanitary napkin, as shown and described.
